UNITED STATES PATENT OFFICE.

HENRY SPRINKEL, OF COOPER, ILLINOIS.

PUMP-SHEATH.

SPECIFICATION forming part of Letters Patent No. 245,323, dated August 9, 1881.

Application filed March 30, 1881. (No model.)

To all whom it may concern:

Be it known that I, HENRY SPRINKEL, a citizen of the United States, residing in the town of Cooper, in the county of Sangamon and State of Illinois, have invented a new and useful Anti-Freezing Pump-Sheath; and I hereby declare the following to be a full, clear, and exact description of the construction and operation of the same, reference being had to the accompanying drawings, making a part of this specification, in which—

Figure 1 is a vertical projection; Fig. 2, a vertical section; Fig. 3, a vertical projection and section combined, and Fig. 4 a horizontal section below the pump-spout.

Letters of reference in the drawings are as follows:

A indicates air-cavity in platform. C indicates outside of pump-sheath. S indicates the pump-stock. P indicates the platform. *a a* indicate air-cavities in sheath. *b b* indicate the furring-strips between the pump stock and outer part of sheath. *d* indicates the cap of sheath.

The sheath is constructed by casing up the stock of the pump from below the lower side of the platform P a few inches to eight inches above the spout, where the water constantly stands. The casing will be covered at the top by the cap *d*, and separated from the stock S one inch by the strips *b b*, and be entirely airtight, except at the bottom under the platform P, which will be left open. Of the furring-strips *b b*, one in the middle of each side of the stock S will end five inches below the cap *d*, so as to allow a channel for the easy passage of air from the air-space on one side of the middle strip to the air-space on the other side. The strips at the corners will run fully up to the cap.

This sheath may also be applied to round or other shaped pumps by making regular channels with the strips, as above, for the passage of air.

The platform P, as constructed with the air-space A, I do not claim in my invention, but it will be used with the sheath to prevent the warm air in the well from coming in close contact with that outside and much lower in temperature.

The result I obtain from the sheath is the keeping of the water in the pump-stock at almost a constant temperature, so that it will not freeze during cold weather. This I do by the self-action of the air in the well, which is always much warmer during cold weather than the outer atmosphere. The warm air in the well rises, and passing up the air-spaces *a a* in the sheath grows cool by being in contact with colder substance, and then sinks to give place to another body of warm air. In that way a regular movement will be obtained, as indicated by the arrows, in the air-spaces *a a* in Fig. 3. By that means the pump-stock will be kept warm, so that it will not fall in temperature below 32°.

What I claim as my invention, and desire to secure by Letters Patent, is—

In combination with a pump-stock, a sheath surrounding said stock and forming air-passages which extend above the water in the stock and are closed at their upper ends, whereby a circulation of the air in the well is maintained and water in the stock protected from freezing.

HENRY SPRINKEL.
